Nicholas Müller
Inventor.

United States Patent Office.

NICHOLAS MÜLLER, OF NEW YORK, N. Y.

Design No. 4,797, dated April 11, 1871.

DESIGN FOR A CLOCK-CASE.

The Schedule referred to in these Letters Patent and making part of the same.

To all whom it may concern:

Be it known that I, NICHOLAS MÜLLER, of the city, county, and State of New York, have invented a new and ornamental Design for a Clock-Case; and I do hereby declare that the following is a full, clear, and exact description thereof, which will enable those skilled in the art to make and use the same, reference being had to the accompanying photographs forming part of this specification, in which—

Figure I represents a front view of my design.

Figure II represents a view of one of the sides.

Similar letters of reference indicate similar parts.

This invention relates to a new and ornamental design for a clock-case, the design being composed of Egyptian ornaments and other ornamental figures, as represented in the several views, and placed respect-

ively on the front and sides of the upper part A A, and on the front and sides of the pedestal or base B B.

The upper portion A A contains the dial-hole d.

The base B B has at the center of its front a central ornament, composed of different members, which proceed from a common center.

What I claim as my invention, and desire to secure by Letters Patent, is—

The design for a clock-case, as herein shown and described.

Signed by me this 25th day of February, 1871.

NICHOLAS MÜLLER.

Witnesses:

LEWIS SKINKLE,

CHARLES KITSCHETT.
